UNITED STATES PATENT OFFICE.

LUIZ PAULO ZEYMER, OF RIO DE JANEIRO, BRAZIL.

SAFETY DEVICE FOR GUNS.

1,256,631.

Specification of Letters Patent. Patented Feb. 19, 1918.

Application filed April 6, 1917. Serial No. 160,193.

To all whom it may concern:

Be it known that I, LUIZ PAULO ZEYMER, a citizen of Brazil, residing at 83 Rua Buenos Aires, Rio de Janeiro, Brazil, have 5 invented new and useful Improvements in Safety Devices for Guns, of which the following is a specification.

It happens very frequently in hunting that the hammer of a gun is caught by the 10 branch of a tree or by the clothing of the hunter and is raised and released quite suddenly, with the result that the gun is accidentally discharged wounding or even killing the bearer or somebody else. The invention 15 refers to a device which, applied to a shooting gun, effectually prevents the hammer from striking the firing pin unless the trigger is pulled, thus doing away with these casualties.

20 In the drawings:

Figure 1 is a lateral fragmentary view of a gun, the mechanism of which is seen through the lock plate and hammer, which are supposed to be transparent;

25 Fig. 2 is a lateral view, in the opposite direction, of the lock plate bearing the mechanism;

Fig. 3 is a perspective view of the tumbler;

30 Fig. 4 is a perspective view of the safety bar and lever which operates it;

Fig. 5 is a lateral view analogous to Fig. 1, of a modified form of the invention to adapt it to the French system of lock;

35 Fig. 6 is a lateral view, in the opposite direction, of the lock plate bearing the mechanism;

Fig. 7 is a perspective view of the tumbler; and

40 Fig. 8 is also a perspective view of the safety cam and lever operating it.

When the hammer 1 is brought back to cocked position the tumbler 2 revolves till the indentation 3 is caught by the end of 45 sear 4 and held by it in that position. The gun is now cocked, and to discharge it the trigger, which is shown as made up of two parts 5 and 6 but which may be made in one piece, must be pulled, part 5 acting on 50 sear 4 and releasing it from the tumbler 2 and consequently the hammer; and part 6 acting on lever 7 which, through a pin 8, engaging a cam slot in the safety bar 9, pushes said bar forward thus allowing the projection 10 of the tumbler to go down past the 55 level of the upper side of the bar, the ham-

mer then striking the firing pin. As soon as the trigger is released the safety bar 9, acted on by spiral spring 11, comes back to the initial position.

It is thus easily seen that the hammer 1 may be raised and released without striking the firing pin, unless the trigger is pulled, because the projection 10 of the tumbler will strike the upper face 12 of the safety 60 bar and be stopped by it before the hammer strikes the firing pin; and the safety bar can be pushed out of the way only through operation of the trigger.

In the modified form, Figs. 5 to 8, as the 70 French lock does not permit the use of the safety bar, a cam 13 is used acted on by a lever 7 and a spring 14 to bring it back to initial position, the form of the tumbler being also slightly modified in that part of it 75 which engages the cam. The fulcrum of lever 7 is placed some distance to the rear of the fulcrum of lever 4 to magnify its action on cam 13. The way the device operates is the same as that above described for the 80 English lock, the cam preventing the projection 10 of the tumbler from going lower than the level of its upper face unless the trigger is pulled, pushing the cam out of the way through the operation of lever 7. 85 Unless this is done the hammer will not strike the firing pin and the gun cannot be discharged.

It is to be understood that the shape or arrangement of the various parts may be modified without departing from the invention. For instance, in Figs. 1, 2 and 4 a flat 90 spring 15 is shown under lever 7, which may or may not be used, as its object is simply to aid spiral spring 11 in raising lever 7 to the 95 initial position.

Having thus described my invention what I claim as new and desire to secure by Letters Patent is:

1. In a gun, in combination, a hammer 100 adapted to operate a firing pin, a tumbler movable with said hammer, a projection on said tumbler which moves downwardly when the hammer moves toward the firing pin, a substantially horizontally movable member 105 the upper face of which normally lies in the path of said projection so as to prevent its downward movement, said member having a free horizontal sliding movement in relation to said projection, a lever having means at 110 one end co-operating with said horizontally movable member to move the same horizon-

tally so as to bring its said upper face out of the path of said projection, trigger-operated means for releasing the hammer, and a trigger for actuating said lever.

5 2. In a gun, in combination, a hammer adapted to operate a firing pin, a tumbler movable with said hammer, a projection on said tumbler which moves downwardly when the hammer moves toward the firing pin, a 10 substantially horizontally movable member the upper face of which normally lies in the path of said projection so as to prevent its downward movement said member having a free horizontal sliding movement in relation to said projection, a lever having means at 15 one end coöoperating with said horizontally movable member to move the same horizontally so as to bring its said upper face out of the path of said projection, trigger-operated 20 means for releasing the hammer, a trigger for actuating said lever, and spring means for returning said lever and said horizontally movable member to normal positions when the hammer is re-cocked.

3. In a gun, in combination, a hammer 25 adapted to operate a firing pin, a tumbler movable with said hammer, a projection on said tumbler which moves downwardly when the hammer moves toward the firing pin, a substantially horizontally movable member 30 the upper face of which normally lies in the path of said projection so as to prevent its downward movement said member having a free horizontal sliding movement in relation to said projection, a lever having a pin at 35 one end engaging an inclined cam slot in said horizontally movable member so as to move the latter horizontally when the lever is oscillated, trigger-operated means for releasing the hammer, and a trigger for actuating said lever.

In testimony whereof I affix my signature in presence of two witnesses.

LUIZ PAULO ZEYMER.
